UNITED STATES PATENT OFFICE.

KENT REGER, OF BUCKHANNON, WEST VIRGINIA.

TRAIN SIGNALING AND STOPPING DEVICE.

1,230,030.

Specification of Letters Patent. Patented June 12, 1917.

Application filed May 6, 1915. Serial No. 26,281.

To all whom it may concern:

Be it known that I, KENT REGER, a citizen of the United States, and a resident of Buckhannon, in the county of Upshur and State of West Virginia, have invented certain new and useful Improvements in Train Signaling and Stopping Devices, of which the following is a specification.

My invention relates to improvements in train signaling and stopping devices, and it consists in the combinations, constructions, and arrangements herein described and claimed.

An object of my invention is to provide a device by means of which any one of a plurality of signals disposed along the track, may be thrown or operated from a central point or station.

A further object of my invention is to provide a device by means of which the operation of the signaling device at any station may be accomplished by electrical means involving the use of one main wire or conductor, in other words, to provide a selective system.

A further object of my invention is to provide train stopping mechanism including trips arranged along the track which may be selectively operated in conjunction with the signal, so as to stop a train or engine at a predetermined point.

The invention involves the use of novel apparatus including devices at each of the stations, said devices being operated synchronously from the central point or station so as to effect the selection.

Other objects and advantages will appear in the following specification and the novel features of the invention will be particularly pointed out in the appended claims.

My invention is illustrated in the accompanying drawings forming part of this application, in which:

Figure 1 is a side view of the central station switch.

Fig. 2 is a plan view of the switch.

Fig. 3 is a detail perspective view of a magnetically operated stop member.

Fig. 4 is a section along the line 4—4 of Fig. 1.

Fig. 5 is a section along the line 5—5 of Fig. 1.

Fig. 6 is a section along the line 6—6 of Fig. 4.

Fig. 7 is a section along the line 7—7 of Fig. 5.

Fig. 8 is a side view of one of the switches which are located at each of the stations.

Fig. 9 is a section along the line 9—9 of Fig. 8.

Fig. 10 is a section along the line 10—10 of Fig. 9.

Fig. 11 is a side view of one of the semaphores or signals.

Fig. 12 is a sectional view through one of trip casings located along the track, the trip being shown in elevation.

Fig. 13 is a section along the line 13—13 of Fig. 12.

Fig. 14 is a side view of a steam line valve lever and the mechanism for releasing the same.

Fig. 15 is a side view of a brake valve operating lever and the releasing mechanism.

Fig. 16 is a plan view showing the releasing mechanism for releasing the throttle lever and the brake valve operating lever.

Fig. 17 is a diagrammatic view showing the electrical circuit between the central station and the various sub stations, and

Fig. 18 is a diagrammatic view showing the circuit on the engine or train.

In carrying out my invention, I provide a central station such as that indicated at C in Fig. 17, at which is disposed a switch, the details of which are best seen in Figs. 1 and 2. From this central station I may control the signals at any number of stations. In Fig. 17 I have shown six of such sub-stations, these being designated by S', S², S³, S⁴, S⁵, and S⁶ respectively.

Referring now to Figs. 1 and 2, I have shown an actuating train. This comprises supporting plates 1 and 2 which are held in spaced relation by a cross member 3 arranged preferably at the four corners. Journaled in the side plates 1 and 2 is a shaft 4 which projects beyond the plate 2 and upon which is a series of conducting circular disks d', d², d³, d⁴, d⁵, and d⁶ respectively, corresponding to the number of stations to be operated. The disks are held in spaced relation by means of metal spacing disks 5. These disks d', d², etc., are preferably made of copper or other conducting material, and are slotted or recessed on their peripheries as shown at r' in Fig. 5. The disks d', d², etc., have recesses r', r², etc., disposed approximately 60° apart since in this particular instance, there are six stations.

On the shaft 4 is also a disk *e* made of fiber or other suitable insulating material, this latter disk having six notches or recesses in its periphery, as shown at *e'*, *e²*, *e³*, etc., in Fig. 4.

5 The disks *d'*, *d²*, etc., are designed to be rotated by the actuating train shown in Figs. 1 and 2. From these figures it will be observed that a weight *W* is attached to the end of a chain or cable 7 which passes 10 over a reel 8 on a shaft 9. The shaft 9 bears a gear 10 which engages a gear 11 on the shaft 4, thereby tending to rotate the disks when the shaft 4 is permitted to revolve.

15 The shaft 4 bears a gear 12 which engages a gear 13 on a stub shaft 14 bearing a gear 15 that in turn engages a pinion 16 on the shaft 17 carrying a stop or escapement wheel 18. It will readily be seen that the wheel 18 must revolve if the shaft 4 revolves, and 20 if the escapement wheel 18 is stopped, the shaft 4 will be stopped likewise.

25 The means for stopping or releasing the escapement wheel 18 consists of a stop lever like that shown at 19 in Fig. 3. This lever is provided with a pivot shaft 20 journaled in the walls 1 and 2, one end of the lever serving as an armature for the magnet *M*, the opposite end being bent laterally as 30 shown at 19₂ so as to engage the teeth of the escapement wheel 18. A laterally extending arm 19₃ projects above the disk *e* but when the armature end of the lever 19 is deenergized, the laterally bent end 19₂ tends to 35 drop down into engagement with the teeth of the escapement wheel 18, see Fig. 4. It is prevented from engaging the teeth of the escapement wheel 18, however, by the engagement of the laterally extending portion 40 of the arm 19₃ with the top of the insulating wheel *e* until the latter has been revolved far enough to bring one of the slots *e'*, *e²*, etc., into alignment with the laterally projecting portion of the arm 19₃ whereupon 45 the latter drops downwardly and thus permits the portion 19₂ to enter between the teeth of the escapement wheel 18, thus stopping the actuating train. As long as the magnet *M* attracts the armature end of the 50 lever 19, the actuating mechanism is free to revolve under the action of the weight *W*, as will be explained later.

55 Secured to one of the side walls such as that shown at 2 is a bracket 23 which bears a cylindrical rod 24 on which is pivotally and slidably mounted a cylindrical sleeve or bearing portion 25 of a laterally extending conducting member or arm 26 having a handle 26₂ at its end. The arm 26 is provided with an integral contact member 26₃ which is arranged to engage any one of a number of conducting pins or pegs extending upwardly from an extension of the bracket 23, the extension being shown at 23₂ 60 and the pins at 23₃. As will be seen Fig. 6,

the bracket 23 is suitably insulated from the plate 2. A companion bracket 23₂ is secured to the plate 1, being insulated from it as clearly shown in Figs. 1 and 2. The pivot rod 24 has one end secured to the bracket 23. The opposite end of the pivot rod 24 is provided with a collar 27. The member 26₃ is provided with a groove 26₂ on its bottom which is arranged to receive the edge of any of the disks *d'*, *d²*, etc., see Fig. 7, so as to let the arm 26 ride on the edge of the disk 70 while the latter is revolving, thereby forming a contact for continuing the current during the revolution of the disk, as will be explained later. The sleeve 25, to which the arm 26 is connected, is of such a length that when it is moved along the rod 24 so as to come into contact with the bracket 23, one edge of the conducting arm 26 will engage the side of the first peg or pin 23₃, i. e., that 75 one nearest to the bracket 23, while the conducting portion 26₃ will ride on the first disk, i. e., the disk *d'*. When the bearing sleeve 25 is in contact with the collar 27, then the arm 26 will rest on the outer disk *d²* while the 80 side of the arm 26 will engage the peg or pin 23₂. When the arm 26 is riding on the edge of any of the intermediate disks, the side faces of the arm will engage pegs on each side as shown in Fig. 6, thus making a 85 good connection between the arm and the bracket 23. The arm 26 may be swung upwardly by means of the handle 26₂ and can be shifted laterally, the sleeve 25 sliding on the rod 24, so as to bring the arm 26 and its 90 contact 26₃ into electrical connection with any of the disks, which as stated before correspond to the different stations. These stations are numbered 1, 2, 3, 4, 5, 6, as shown 95 on the bracket 23₂ in Fig. 2.

100 In order to prevent the actuating train from running too fast, I provide a centrifugal governor, the shaft 30 of which is journaled in the side walls 1 and 2. Secured to the shaft is a pinion 31 which meshes with 105 the escapement wheel 18. The governor is also provided with arms 32 which are secured to the shaft, and has a slidable sleeve 33 pivotally connected by links 34 with the arms 32, said sleeve passing through a slotted 110 arm 35 and being provided with a friction disk 36, see Fig. 1. It is obvious that when the machine is running too fast, the arms 32 will be spread apart thus drawing on the sleeve 33 and bringing the friction disk up 115 against the face of the arm 35. The latter is secured at one end to the plate 1, and is, in fact, a spring arm, so that the friction exerted between the disk 36 and the spring arm 35 will gradually slow down the apparatus, or 120 rather, it will prevent too rapid a motion.

125 The apparatus which is installed at the various stations, as far as the actuating train and the means for stopping the same, is concerned, is practically identical with 130

that at the central station. In the drawings I have indicated the parts which are similar to the parts at the central station, by the same reference letters with the addition of the subscript *s*. The apparatus is best shown in Figs. 8 and 9. In these figures it will be observed that the insulating disk *es* is provided with the slots *e's*, *e²s*, *e³s*, *e⁴s*, etc. In Fig. 9, the arm *19ys* is shown in the slot *e³s*. The disk shown in the figure is arranged for the station *S³*, see Fig. 17, and it will be observed that adjacent to the slot *e³s* there is a conducting member 40 which the arm *19ys* is adapted to engage just before its entrance into the slot *e³s*. The other stations have one conducting member like the member 40, adjacent one of the six slots in the wheel *es*. For the station 1, its wheel *es* would have the conducting member 40 adjacent to the slot *e's*; for the station *S²*, the wheel would have the conducting segment adjacent to the slot *e²s*, and so on as shown in Fig. 17.

At each substation a signal is arranged like that shown in Fig. 11. This consists of a semaphore arm 41 which is pivotally mounted at 42 upon a mast or upright 43. The normal or "clear" position of the signal is vertical and it is held in this position by means of a catch 44 which is pivoted at 45 and is normally acted on by a spring 46. The end of the catch on the opposite side of the pivot 45 has an armature 47 associated with a magnet 48. When the armature 47 is attracted it will release the arm 41, thereby permitting it to swing down into the "danger" position shown in dotted lines in Fig. 1.

Associated with each substation is one or more of the trip mechanisms best shown in Fig. 12. This consists of a casing 49 in which is mounted a plunger 50 pressed upon by a spring 51 and bearing at its top a horizontally disposed impact member 52, curved at both ends. Normally the plunger 50 is held by means of a spring pressed catch or detent 53 which may be actuated on by a magnet 54 to release the plunger, thereby permitting the member 52 to rise into the dotted line position where it may engage contact members 55 and 56 carried by the engine or train.

The apparatus on the engine is comparatively simple. It consists of a catch 57 under the tension of a spring 58 which may be actuated by a magnet 59 to release the steam line valve lever 60. A similar arrangement is used in connection with the brake valve operating lever 61, see Fig. 15.

In Fig. 17 I have shown diagrammatically the circuit connection between the central station C and the stations *S'*, *S²*, *S³*, etc. The operation of this signaling and train stopping mechanism will best be understood by taking a specific example.

Let us assume that the operator at the central station C wishes to signal a certain train

to stop at station *S³*, and also wishes to set a trip so that if the engineer does not obey a signal, the train will be stopped in spite of his actions. The operator at the central station C lifts the handle 26*x* and slides the latter longitudinally of the rod 24 until the arm 26 is over the disk *d³* corresponding to the station *S³*. He then lowers the handle so that the contact 26*y* engages the edge of the disk *d³*. As long as the contact 26*y* is engaging the disk *d³*, current will flow from the battery B, see Fig. 17, through the main line wire L, from ground through the magnet M, shaft 4, disk *d³*, 26, and back to battery. It will be noted that the magnets M, M'S, M²S, etc., all act simultaneously. The actuating mechanism at each station begins to revolve its disk *e*, while the actuating mechanism at the central station begins to revolve the six disks *d'*, *d²*, etc., as well as the disk *e*. The apparatus at the central station and at the substations continues to revolve until the slot or groove *r³* of the disk *d³* comes into registration with the contact 26*y*, whereupon the current will be broken at this point. This, it will be observed from Fig. 17, is just before the end 19*y* of the lever 19 reaches the slot or recess *e³s* of the disk *e*. A slight further rotation will permit the arm to enter the slot and thus permit the laterally bent end 19*x* of the lever to engage the escapement wheel 18 of the central station, thus stopping the actuating mechanism.

When the disk *e* of the substation starts to revolve by the simultaneous action of the control magnets, M'S, M²S, M³S, etc., they revolve synchronously owing to the action of the governor. When the current is cut off from the main line L by the registration of the slot or recess *r* of disk *d³* with the contact 26*y*, see Fig. 17, then the levers 19*s'*, 19*s²*, etc., will drop downwardly simultaneously. The cutting off of the current is timed so that the lever drops down just after the slot in the disk *e* at the station at which the signal is to be shown, which is immediately in front of, or which precedes the slot in which it is desired that the end of the lever shall rest, has passed the end of the lever. Consider Fig. 17: The end of the lever 19*s³* drops downwardly just after the recess *e³s* has passed the end of the lever with the disk *e* rotating in the direction shown by the arrow. The end of the lever 19*s³* will therefore rest on the surface of the disk *e*. The ends of the other levers corresponding to 19*s³* at the various stations, will rest on their respective disks. Further rotation of the disk *e* at the various stations will bring the end of the lever 19*s³* into engagement with the contact 40 at station *S³* an instant prior to its registration with the recess *e³s*. This condition is shown in Fig. 17 at station *S³*. It will be observed that 130

the levers corresponding to the lever 19^{s³} at the other stations, are none of them in engagement with the contacts at the peripheries of the disks *e*, since, as stated before, these contacts are placed adjacent to the particular recess at which it is desired to stop the rotation of the disk. With the end of the lever 19^{s³} engaging the contact 40, a circuit will be established from the local battery *B'*, through these contacts and through the release magnet 54^{s³} which will release the catch to permit the trip 52^{s³} to be projected into the path of the spring contacts 56 and 55. The closing of these contacts will complete a local circuit on the engine from the battery *B²*, through the magnet 59 of the steam line valve releasing mechanism, and also of the brake valve lever releasing mechanism. This will cause the steam to be shut off and the brakes to be set, thereby causing the stopping of the train.

At the same time the magnet 48^{s³} will cause the operation of the trip 44^{s³} to release the semaphore 41^{s³} so as to bring it to "danger" position shown in Fig. 17.

It will be observed that the local circuit through the battery *B'* is closed only for an instant, so that when it is desired to reset the semaphore, it may be done by pulling downwardly on a cord or other suitable member such as that shown at 70 in Fig. 17 at station *S³*. The trip may also be reset by pushing downwardly on it until it comes into engagement with the catch.

I have explained how the signal and trip at one of the stations may be operated, but it is obvious that the others are operated in the same manner. The recesses such as that shown at *r³* in the disk *d³* which cause the cutting off of the current, as already explained, are arranged in definite relation with respect to the recesses *e¹s³*, *e²s³*, *e³s³*, etc., so that all the operator at the central station has to do, is to place the conducting arm upon the proper disk at the central station as described, whereupon the apparatus will start up and the signal and trip will be thrown.

It will be seen from the description given that the apparatus is positive in action and requires only slight effort on the part of the central station operator to correctly manipulate the device. I am aware that other forms of the device based upon the same general plan, might be made without departing from the spirit of the invention.

I claim:

1. In a train signaling and stopping device, a selector switch comprising a plurality of movable conducting disks having a common axis, each of said disks being provided with a recess on its periphery, the recesses of the disks being disposed in successive steps with respect to their angular

disposition around their common axis, a single conducting arm arranged to engage the periphery of any of said disks, an insulating disk having a series of radially extending notches at the periphery of the disks, an actuating mechanism for rotating all of said disks including an escapement wheel, means normally in engagement with said escapement wheel for stopping the rotation of said insulating disks, and electromagnetic means for withdrawing the said stopping means clear of the escapement wheel and thereby permitting the rotation of the disks.

2. In a train signaling and stopping device, a selector switch comprising a plurality of movable conducting disks having a common axis, each of said disks being provided with a recess on its periphery, the recesses of the disks being disposed in successive steps with respect to their angular disposition around their common axis, a single conducting arm arranged to engage the periphery of any of said disks, an insulating disk having a series of radially extending notches at the periphery of the disks, an actuating mechanism for rotating all of said disks including an escapement wheel, a lever having one end arranged to engage said escapement wheel for stopping the actuating mechanism, an electro-magnet acting on the opposite end of the lever for raising the same, and an arm carried by said lever and arranged to extend over and rest upon the periphery of said insulating disks.

3. In a train signaling and stopping device, a selector switch comprising a plurality of conducting disks, said disks being mounted to rotate on a common axis, each of said disks being provided with a single recess in its periphery, the recesses of the disks being disposed in successive steps with respect to their angular disposition around their common axis, and a single conducting arm arranged to engage the periphery of any of said disks.

4. In a train signaling and stopping device, a selector switch comprising a plurality of conducting disks, said disks being mounted to rotate on a common axis, each of said disks being provided with a single recess in its periphery, the recesses of the disks being disposed in successive steps with respect to their angular disposition around their common axis, a single conducting arm arranged to engage the periphery of any of said disks, means for rotating the disks, the rotation of the disks serving to bring the conducting arm eventually into registration with the recess in the periphery of the disk.

5. In a train signaling and stopping device, a selector switch comprising a plurality of conducting disks, said disks being mounted to rotate on a common axis, each

- of said disks being provided with a recess in its periphery, the recesses of the disks being disposed in successive steps with respect to their angular disposition around their common axis, a single conducting arm arranged to engage the periphery of any of the disks, means for rotating the disks, and electro-magnetic means for stopping the rotation of the disks, said electro-magnetic means being energized by current through the disks and the conducting arm whereby when the recess in the disk is in registration with the conducting arm the current will be cut off and the rotation of the disks will be stopped.
6. In a train signaling and stopping device, a selector switch comprising a plurality of conducting disks, said disks being mounted to rotate on a common axis, each of said disks being provided with a single recess in its periphery, the recesses of the disks being disposed in successive steps with respect to their angular disposition around their common axis, a single conducting arm arranged to engage the periphery of any of said disks, means for rotating the disks, the rotation of the disks serving to bring the conducting arm eventually into registration with the recess in the periphery of the disk, and means for regulating the speed of rotation of the disks.
7. In a train signaling and stopping device, a selector switch comprising a plurality of conducting disks, said disks being mounted to rotate on a common axis, each of said disks being provided with a single recess in its periphery, the recesses of the disks being disposed in successive steps with respect to their angular disposition around their common axis, a single conducting arm arranged to engage the periphery of any of said disks, means for rotating the disks, the rotation of the disks serving to bring the conducting arm eventually into registration with the recess in the periphery of the disk, and a governor for regulating the speed of rotation of the disks.
8. In a train signaling and stopping device, a frame, a rotatable shaft mounted on said frame, a plurality of parallel conducting disks carried by said shaft, the periphery of each disk being provided with a single recess extending toward the center of the shaft, the recesses of the various disks being in stepped relation with one another around the shaft, a second shaft parallel with said first named shaft, a single arm loosely mounted on said second named shaft, and slideable on said shaft longitudinally of the latter, said arm being arranged to engage any of said conducting disks, a series of contacting members, one of said contacting members being engaged by the arm during engagement with any of said disks.
9. In a train signaling and stopping device, a frame, a rotatable shaft mounted on
- said frame, a plurality of parallel conducting disks carried by said shaft, the periphery of each disk being provided with a single recess extending toward the center of the shaft, the recesses of the various disks being in stepped relation with one another around the shaft, a second shaft parallel with said first named shaft, a single arm loosely mounted on said second named shaft and slideable on said shaft longitudinally of the latter, said arm being arranged to engage any of said conducting disks, a series of contacting members, one of said contacting members being engaged by the arm during engagement with any of said disks, an actuating train for rotating the shaft upon which the disks are mounted, electro-magnetic means for stopping the actuating train.
10. In a train signaling and stopping device, a frame, a rotatable shaft mounted on said frame, a plurality of parallel conducting disks carried by said shaft, the periphery of each disk being provided with a recess extending toward the center of the shaft, the recesses of the various disks being in stepped relation with one another around the shaft, a second shaft parallel with said first named shaft, a single arm loosely mounted on said second named shaft and slideable on said shaft longitudinally of the latter, said arm being arranged to engage any of said conducting disks, a series of contacting members, one of said contacting members being engaged by the arm during engagement with any of said disks, an actuating train for rotating the shaft upon which the disks are mounted, and electro-magnetic means for stopping the actuating train.
11. In a train signaling and stopping device, a frame, a rotatable shaft mounted on said frame, a plurality of parallel conducting disks carried by said shaft, the periphery of each disk being provided with a recess extending toward the center of the shaft, the recesses of the various disks being in stepped relation with one another around the shaft, a second shaft parallel with said first named shaft, a single arm loosely mounted on said second named shaft and slideable on said shaft longitudinally of the latter, said arm being arranged to engage any of said conducting disks, a series of contacting members, one of said contacting members being engaged by the arm during engagement with any of said disks, an actuating train for rotating the shaft upon which the disks are mounted, electro-magnetic means controlled by the relative position of the disks, and a conducting arm for stopping the actuating train.
12. In a train signaling and stopping device, a frame, a rotatable shaft mounted on said frame, a plurality of parallel conducting disks carried by said shaft, the periphery of each disk being provided with a recess extending toward the center of the shaft, the recesses of the various disks being in stepped relation with one another around the shaft, a second shaft parallel with said first named shaft, a single arm loosely mounted on said second named shaft and slideable on said shaft longitudinally of the latter, said arm being arranged to engage any of said conducting disks, a series of contacting members, one of said contacting members being engaged by the arm during engagement with any of said disks, an actuating train for rotating the shaft upon which the disks are mounted, electro-magnetic means controlled by the relative position of the disks, and a conducting arm for stopping the actuating train, said last-named means comprising a movable lever arranged to move into a portion of said actuating train.

- train, a magnet for operating the lever, and an energizing circuit for said magnet, said energizing circuit including said conducting arm and a disk with which it engages.
- 5 12. In a train signaling and stopping device, a switch comprising an insulating disk, a series of radially extending notches at the periphery of the disk, a conductor disposed adjacent to one of said notches, an actuating mechanism for rotating the said disk including an escapement wheel, means normally in engagement with said escapement wheel for stopping the rotation of said insulating disk, and electro-magnetic means 10 for raising said stopping means clear of the escapement wheel and thereby permitting the rotation of the disk.
- 15 13. In a train signaling and stopping device, a switch comprising an insulating disk, a series of radially extending notches at the periphery of the disk, a conductor disposed adjacent to one of said notches, an actuating mechanism for rotating said disk including an escapement wheel, a lever having one end 20 arranged to engage said escapement wheel for stopping the actuating mechanism, an electro-magnet actuating on the opposite end of the lever for raising the same, and an arm carried by said lever and arranged to extend over and rest upon the periphery of the insulating disk.
- 25 14. In a train signaling and stopping device, a switch comprising an insulating disk, a series of radially extending notches at the 30 periphery of the disk, a conductor disposed adjacent to one of said notches, an actuating mechanism for rotating said disk including
- an escapement wheel, a lever having one end arranged to engage said escapement wheel for stopping the actuating mechanism, an electro-magnet actuating on the opposite end of the lever for raising the same, and an arm carried by said lever and arranged to extend over and rest upon the periphery of the insulating disk, the passage of the conducting member carried by the disk past the last named arm serving to effect electrical connection between the conducting member and the arm.
- 35 15. In a train signaling and stopping device, a switch comprising an insulating disk, a series of radially extending notches at the periphery of the disk, a conductor disposed adjacent to one of said notches, an actuating mechanism for rotating said disk including an escapement wheel, a lever having one end arranged to engage said escapement wheel for stopping the actuating mechanism, an electro-magnet actuating on the opposite end of the lever for raising the same, and an arm carried by the said lever and arranged to extend over and rest upon the periphery of the insulating disk, the passage of the conducting member carried by the disk past the last-named arm serving to effect electrical connection between the conducting member and the arm, and a local circuit including a signal operating device adapted to be closed by the engagement of the arm with the conducting member.

KENT REGER.
